UNITED STATES PATENT OFFICE.

FRANK J. HEGMAN, OF DAYTON, OHIO.

DESIGN FOR A FOOTSTOOL.

SPECIFICATION forming part of Design No. 30,193, dated February 14, 1899.

Application filed March 21, 1898. Serial No. 674,689. Term of patent 3½ years.

To all whom it may concern:

Be it known that I, FRANK J. HEGMAN, a citizen of the United States, residing at Dayton, in the county of Montgomery and State of Ohio, have invented and produced a new and original Design for a Footstool; and I do declare the following to be a full, clear, and exact description of the same, reference being had to the accompanying drawing, forming a part thereof.

As shown in the drawing, the leading and material feature of my design consists of a series of parts.

The leg 1 is convex, with a broad scroll top 5 with carved front at 5, with a beaded molding 6, with the foot 4, carved with cross-lines, with a top 2 with acorn-shaped pendent ornaments 3.

Having described my invention, what I claim as new, and desire to secure by Letters Patent, is—

The design for a footstool as herein shown and described.

In testimony whereof I affix my signature in presence of two witnesses.

FRANK J. HEGMAN.
